UNITED STATES PATENT OFFICE

91,693

DESIGN FOR A DISPLAY STAND

Noah Van Cleef, Chicago, Ill., assignor to Van Cleef Bros., Chicago, Ill., a partnership consisting of Noah Van Cleef, Felix Van Cleef, Maxime Van Cleef, and Paul Van Cleef

Application December 14, 1933, Serial No. 50,068

Term of patent 7 years

To all whom it may concern:

Be it known that I, NOAH VAN CLEEF, a citizen of the United States, residing at Chicago, in the county of Cook and State of Illinois, have invented a new, original, and ornamental Design for Display Stands, of which the following is a specification, reference being had to the accompanying drawing forming a part thereof.

I claim:

The ornamental design for a display stand substantially as shown.

NOAH VAN CLEEF.
